PLASTER BASE

Walter F. Schulz, Youngstown, Ohio, assignor to
Truscon Steel Company, Youngstown, Ohio, a
corporation of Michigan

Application August 16, 1933, Serial No. 685,481

2 Claims. (Cl. 72—116)

The present invention relates to plaster bases of sheet metal, and the object is to provide a structure which may be made of light gauge material, is extremely cheap to manufacture, can be applied to the supports with ease and expedition, and when in place constitutes a carrier or base for the plaster which will most effectively support the same, and will eliminate discoloration due to "breathing" and "dusting" that is common with wood laths. Furthermore it results in a great saving of plaster due to the character of the structure and its mounting on the studding or other supports, and in addition effecting a tremendous saving in dead weight load wherever employed, but especially in tall buildings.

In the accompanying drawing:

Figure 1 is a face view of a portion of a wall showing the plaster base in place.

Figure 2 is a vertical cross sectional view illustrating the complete wall with the plaster in place.

Figure 3 is a detail rear elevation to show outstanding flanges around the slots.

Figure 4 is a detail view showing the means for securing the lath to metal supports.

In the embodiment disclosed spaced studs 3 are provided which may be of the usual form and either of wood or metal, the plaster base being applicable to either. The base is in the form of a relatively light sheet of metal 4 which is provided with a plurality of intermediate longitudinal ribs 5, these ribs being of V-shape in cross section. One margin of the sheet is provided with a rearwardly turned flange 6, the opposite margin also has a rearwardly turned flange 7 having an outstanding edge portion 8, providing a groove 9 along said edge. The portions of the sheet between the ribs 5 and between said ribs and flanges 6 and 7 are provided with sets of longitudinally disposed slots 10, the deformation of the material in the production of such slots being rearwardly disposed, providing flanges 11 around the edges of said slots. These flanges, as will be clear by reference to Figure 2 are of less depth than the depth of the ribs 5 and flanges 6 and 7 and lie between the same. The slots are arranged in rows, the slots of each row being located end-to-end, and staggered with relation to the adjacent rows. More than that, as clearly shown in Figure 1, the slots on opposite sides of a rib are located side by side, thereby providing convenient means for passing fastening wires, as 12, through the same when the sheets are secured by said means. It will be understood that any suitable means however may be employed

and that wires or like fasteners are particularly useful where the studs or supports are of metal.

In the application of this structure to the supports 3 the sheets are arranged horizontally, with the edges of the ribs against the supports, as shown in Figure 2. As a consequence it will be evident that the main body of the plaster base is spaced from the supports or studs and that as a consequence the slots 10 have their rear sides entirely open and not obstructed by the studs. It will also be noted that the V-shaped formation of the ribs provides in the outer side of the sheet correspondingly formed channels 13 and that these channels are relatively narrow. The ribs extending transversely of the studs constitute effective reinforcements or stiffening agents for the intermediate portions of the sheet, while the marginal flanges 6 and 7 act as stiffening means for the edges of the sheet. It will also be noted by reference to Figure 2 that the flange 6 of one sheet will engage in the marginal groove 9 of an adjacent sheet, so that the parts are interlocked.

When the complete plaster base for a wall is thus assembled and secured, it provides a smooth outer surface without obstruction to the sweep of the plastering tools and consequently a thin sheet of plaster can be easily applied. When so applied by reason of the V-formation of the channels which flare outwardly toward the exposed surface, these channels will readily receive the plaster and be substantially filled with the same. As they are narrow, however, they do not require a large amount of plaster to fill them. The plaster will pass through the narrow slots 10 and form keys over and around the flanges 11 made by the deformation of the metal in producing said slots.

The consequence is that a wall structure is provided in which the plaster is smooth and even and is not materially subject to cracking or dislodgment. At the same time the plaster coat is thin but it is effectively keyed to the base and is further held, especially while green, against slipping by the ribs formed thereon by the plaster entering the channels 13. The plaster base moreover is spaced from the supports or studding except for narrow lines of contact due also to the form of the ribs 5. It will be obvious that the base can be readily and cheaply manufactured and easily applied, and that the completed structure will be light in weight, thus materially decreasing the dead load that must be carried by the other structural parts of the building.

From the foregoing, it is thought that the construction, operation and many advantages of the

herein described invention will be apparent to those skilled in the art without further description, and it will be understood that various changes in the size, shape, proportion and minor details of construction may be resorted to without departing from the spirit or sacrificing any of the advantages of the invention.

What I claim is:

1. A wall structure including spaced supports 10 and a plaster base on said supports, said base including an elongated metal sheet extending across a plurality of the supports and having spaced ribs formed therein, said ribs being of substantially V-form in cross section and disposed across the supports with their closed edges bearing against the same, the portions of the sheets between the ribs being thereby spaced from the supports and having substantially smooth outer faces interrupted by substantially V-shaped channels formed 20 by the ribs and said portions being each provided with rearwardly punched slots that are disposed longitudinally of the ribs and channels, and transversely of the supports, said slots being arranged in rows end to end parallel with the channels, a 25 plurality of said rows being located between ad-

jacent channels, the material deformed by the provision of the slots being rearwardly offset along the edges of the slots and being maintained in spaced relation to the supports by said ribs.

2. A plaster base comprising a metal sheet having spaced longitudinally disposed ribs on its rear side that are substantially V-shaped in cross section, the rear edges of said ribs constituting bearings against the supports to which the sheet is fastened and the portions of the sheet between the ribs being flat and normally lying in substantially a common plane and being spaced by the ribs from said supports, said ribs forming spaced substantially parallel open V-shaped channels in the outer plaster-receiving face of the sheet, and said portions of the sheet between the channels having a plurality of rows of substantially parallel elongated plaster key-receiving slots punched rearwardly through the sheet between adjacent ribs, the slots being substantially parallel to the channels and the deformed material around the slots forming rearwardly extending flanges between and parallel to the ribs and materially of less depth than the same. 15
